UNITED STATES PATENT OFFICE.

FRANK B. SCHUYLER, OF BERKELEY, CALIFORNIA, ASSIGNOR TO JOHNSON WASHER COMPANY, OF OAKLAND, CALIFORNIA, A CORPORATION OF CALIFORNIA.

WRINGER ATTACHMENT.

Application filed October 2, 1924. Serial No. 741,142.

This invention relates to a wringer attachment for clothes, washing machines, wash tubs, trays, and the like.

The object of the present invention is to provide a clothes wringer driving and supporting mechanism which may be attached to an ordinary wash tray having two or more compartments formed therein; to provide a clothes wringer driving and supporting mechanism which is adapted to cooperate with an ordinary domestic type of power driven washing machine, and also adapted to be driven thereby; to provide a clothes wringer driving and supporting mechanism which permits movement of the clothes wringer from one compartment of a wash tray to another; and further, to provide a gear transmission whereby power may be transmitted to the wringer rolls both ahead and reverse, and whereby a neutral position may be assumed.

One form which my invention may assume is exemplified in the following description and illustrated in the accompanying drawings, in which—

Fig. 1 is a perspective view showing the application of the invention.

Fig. 2 is an enlarged detail sectional view showing the method of securing the wringer driving and supporting mechanism with relation to the wash trays.

Fig. 3 is a cross-section of the wringer driving and supporting mechanism, said section being taken through the transmission case and also showing a portion of the wringer and the rolls carried thereby.

Fig. 4 is an end view of the transmission case and the gear shifting mechanism, the view being a section taken on line 4—4 of Fig. 3.

Fig. 5 is a longitudinal plan section, taken on line 5—5 of Fig. 1, said view being broken away to permit removal of the transmission case.

Fig. 6 is a plan view of the transmission case.

Referring to the drawings in detail, and particularly to Fig. 1, A indicates in general a domestic type of clothes washing machine, B a standard form of cement wash tray, and C a standard form of clothes wringer.

The invention forming the subject matter of the present invention is a clothes wringer supporting and driving mechanism which is generally indicated at D. This mecha-

nism consists of a pair of end frames or standards 2 suitably secured to a base plate or board 3. Formed in each standard 2 is a bearing member 4 and extending through the bearing members and journalled therein is a main driving shaft 5. This shaft has a key-way or spline formed therein, as indicated at 6, and this extends from end to end of the shaft for purposes hereinafter to be described. The shaft 5 is adapted to be driven from either end and it is particularly intended that it should be driven in unison with a washing machine such as indicated at A. This machine is driven by means of an electric motor E, said motor transmitting power to a vertical shaft 7 which in turn transmits power to the impeller or other agitating device disposed within the washing machine. Power is in this instance transmitted from the vertical shaft 7 to a bevel gear 8. This is journalled in a bearing 9 formed in an extended portion 10 of an enclosing housing such as shown in Figs. 1 and 5. The gear shaft 11 carrying the bevel gear 8 is recessed or hollow in one end and a bayonet slot is formed in the shaft as indicated at 12, the recessed end being provided for the reception of an intermediate shaft 13, and the bayonet slot for the reception of a pin 14 carried thereby. The bayonet slot and pin form a driving connection between the shafts 11 and 13 and shaft 13 in turn serves the function of driving the shaft 5, this being accomplished by recessing the ends of the shaft 5, as indicated at 15, and securing the shaft 13 therein, for instance, by means of a setscrew 16. The connections 14 and 16 serve the function of universal joints and thus eliminate the necessity of any exact aligning of the shafts when installing the wringer attachment.

The base or board section 3 upon which the standards 2 are carried is secured to the wash tray B in a substantial and simple manner; that is, the base board is drilled or perforated adjacent each end and bolts such as indicated at 17 (see Fig. 2) are passed therethrough. The lower ends of these bolts are threaded to carry hook-shaped members 17^a to engage the shanks or inner ends of water faucets 18. This manner of securing the wringer attachment is exceedingly simple and requires no skill. It may, therefore, be installed by practically any one.

The wringer attachment serves the func-

tion of driving the wringer C and also that of supporting one end of the same. This is accomplished in the following manner: Slidably mounted on the shaft 5 is a gear transmission case 20 (see Figs. 3, 4 and 6), and slidably mounted on the shaft within the transmission case is a pair of bevel gears 21 and 22. These gears are splined to the shaft 5 and as such are constantly rotated in unit with the same. Extending through one side of the gear case and journaled therein is a shaft 23. A bevel gear 24 is secured on the outer end of the shaft, and gears 21 and 22 are adapted to be thrown into mesh therewith and they are also adapted to assume a neutral position when the wringer is not in operation. The shaft 23 is connected to the shaft 25 of the lower wringer roll 26 through means of a pin and slot connection such as indicated at 27, and the upper roller is merely frictionally driven thereby. The wringer frame generally indicated at C is secured to the transmission case by means of bolts 30 and as such is supported thereby; that is, one end of the wringer is supported by the transmission case but the opposite end of the wringer is provided with a foot which rests on the outer edge of the wash tray, as indicated at 31 (see Fig. 1). The transmission case, to which the wringer is secured, is freely slidable on the shaft and is freely turnable thereon, and the outer end of the wringer may thus be grasped and lifted upwardly and then pushed from one end to another of the main shaft 5, when it is desired to shift its position from one wash tray compartment to another; or the foot 31 may slide along the outer edge of the wash tray when changing the position of the wringer.

Means are provided for shifting the gears 21 and 22 into or out of mesh with relation to the gear 24, and also to maintain the gears 21 and 22 in neutral position with relation thereto. The means employed is a cover member 35. This cover is slidably mounted on the transmission case 20, and it is provided with a pair of downwardly extending lugs 36 one at each end. These lugs engage the ends of the gears 21 and 22 and any movement imparted to the cover member 35 will thus simultaneously be imparted to the gears 21 and 22. To move the cover a shifting lever 37 has been employed. A pin 38 carried by this lever engages a forked extension 39 of the cover and movement imparted by means of the lever 37 is thus transmitted to the cover. The lever is also provided with a segmental extension such as indicated at 40. This extension has three recesses formed therein as indicated at 41. These recesses are alternatively engaged by a spring-actuated pin 42. This pin serves the function of frictionally securing the lever 37 against movement; that is, the tension of the spring on the pin 42 is sufficient to secure the

lever in any one of three positions desired, to-wit, neutral, ahead or reverse. The central depression 41 maintains the gears 21 and 22 in neutral position, while the end depressions or recesses 41 maintain the gears in mesh with the gear 24 either for ahead or reverse movement. A neutral position is necessary as shaft 5 is continuously driven when the washing machine is in operation, and it is obvious that power should not be transmitted to the wringer except when it is required.

The wringer attachment here shown was designed with the idea in view that a housewife could do her washing without moving the washing machine and at the same time be able to wring from the washing machine into the trays or from the trays into a clothes basket. The attachment was also designed with the idea in mind of leaving a clear passage in front of the wash trays, this being accomplished by placing the washing machine at one end instead of in front of the trays, as is usually the case. By placing the washing machine at one end or another of the wash trays, it is possible to permanently connect it with a sewer and also to install permanent water faucets. The main shaft of the wringer attachment is so designed that it may be driven from either end. This permits the washing machine to be placed at either end of the wash trays and permits it to be used in a narrow wash-room. The device as a whole is exceedingly simple and substantial, and it is easy to operate and as such has proved a great convenience as far as the average household is concerned.

While certain features of the present invention are more or less specifically illustrated, I wish it understood that various changes in form and proportion may be resorted to within the scope of the appended claims. I similarly wish it understood that the materials and finish of the several parts employed may be such as the experience and judgment of the manufacturer may dictate or various uses may demand.

Having thus described my invention, what I claim and desire to secure by Letters Patent is—

1. A clothes wringer and driving and supporting mechanism therefor comprising a frame, a main shaft extending from end to end of the frame and journaled therein, a gear transmission case slidably mounted on said shaft, a clothes wringer secured to said gear transmission case, said transmission case and clothes wringer being movable from end to end of the shaft, wringing rollers in the wringer, a pair of interspaced bevel gears splined on the main shaft and disposed within the transmission case, a bevel gear secured to a shaft carrying one of the wringer rolls, said bevel gears being also disposed within the transmission case, a sliding

cover on the transmission case, lugs on said cover engaging the pair of bevel gears, and means for transmitting movement to the cover and the gears to shift the same either 5 to a neutral position with relation to the single bevel gear, or to a position where one or another of the pair of bevel gears will intermesh therewith.

2. A clothes wringer and driving and supporting mechanism therefor comprising a 10 frame, a main shaft extending from end to end of the frame and journaled therein, a gear transmission case slidably mounted on said shaft, a clothes wringer secured to said 15 gear transmission case, said transmission case and clothes wringer being movable from end to end of the shaft, wringing rollers in

the wringer, a pair of interspaced bevel gears splined on the main shaft and disposed within the transmission case, a bevel gear secured 20 to a shaft carrying one of the wringer rolls, said bevel gears being also disposed within the transmission case, a sliding cover on the transmission case, lugs on the cover engaging the pair of bevel gears and adapted to shift 25 said gears into mesh with the single bevel gear, or into a neutral position with relation thereto, a hand-operated lever for transmitting movement to the cover and the pair of bevel gears, and a spring latch for locking 30 said lever in reverse, neutral and ahead positions.

FRANK B. SCHUYLER.
